(57) **CLAIM**

The ornamental design for a blade for a blender, as shown and described.

DESCRIPTION

FIG. 1 is a front perspective view of a blade for a blender, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof, shown in enlarged scale; and,

FIG. 8 is a bottom plan view thereof, shown in enlarged scale.

The broken lines in the drawings show portions of the blade for a blender, which form no part of the claimed design.

The dot-dash boundary lines shown in FIG. 1 immediately adjacent to the claimed areas represent the boundaries of the design and form no part thereof.
